UNITED STATES PATENT OFFICE.

OSCAR GASSETT, OF BOSTON, MASSACHUSETTS.

SYSTEM OF ELECTRIC LIGHTING.

SPECIFICATION forming part of Letters Patent No. 310,663, dated January 13, 1885.

Application filed October 8, 1883. (No model.)

To all whom it may concern:

Be it known that I, OSCAR GASSETT, of Boston, county of Suffolk, State of Massachusetts, have invented an Improvement in Systems of Electric Lighting, of which the following description, in connection with the accompanying drawing, is a specification, like letters on the drawing representing like parts.

My invention relates to a system of lighting by electricity, and is embodied in an apparatus in which each house or building to be lighted contains its own electric circuit and generator for electricity and a motor to operate the generator, while the power for actuating the motors of a large number of buildings or stations is distributed from a common or central station. The power is distributed by means of compressed air, there being at the main or central station a compressing-engine and reservoir to retain a considerable quantity of compressed air, and the system also comprises small reservoirs at the different sub-stations or buildings, containing a sufficient amount of compressed air to actuate the motor for a considerable length of time without further supply from the main station.

The invention consists in the general arrangement and combination of the different parts of the apparatus, and also in various details hereinafter specified.

The drawing shows in a diagram a portion of a system of electric lighting embodying this invention.

At the main or central station a motor of any suitable or usual construction is employed to operate an air-compressing apparatus, A, by which air is compressed into a suitable reservoir, B, of considerable size, so that the air-compressor A may remain continually in operation, although the air is drawn from the reservoir B only during a portion of the time. From the said reservoir B the compressed air is conveyed by suitable ducts or pipes, a, having branches leading to all the points that are to be supplied with power from the main or central motor.

Each building or sub-station to be lighted is preferably provided with a reservoir, b, into which air is received from the pipe a, which

is provided with a check-valve, c, to prevent the return of air from the reservoir b in case the pressure in the pipe should be reduced. From the reservoir b the air is conveyed by a pipe, C, to a pressure-regulating device, d, of any suitable or usual construction, from which it issues with a uniform pressure into a pipe, e, which supplies the motor f, and actuates the generator g, that is to produce the current employed for lighting. The motor f is preferably one of the rotary order, having the armature of the generator g connected directly with its shaft.

The passage of air from the reservoir b to the pressure-regulator d and motor f is controlled by a valve, h, the stem of which is provided with a bell-crank lever, h', one arm of which is acted upon by a weight, h², tending to move it in the direction to close the valve, and the other arm of which is connected with a piston, k, operating in a cylinder, k', supplied with air from a chest, k², connected with the pipe c and reservoir b, the pressure of the air when admitted to the cylinder k' moving the piston k and connected lever h' in the direction to open the valve h. The admission of air into the cylinder k' from the chest k² to operate the valve h, as thus described, is controlled by a small tapering valve, m, connected with the armature of an electro-magnet, m'. The piston k has a loose fit in the cylinder k', but when forced forward by the air when the valve m is opened comes to a seat upon the head k³ of the cylinder, preventing the escape of air between the piston and cylinder. When, however, the valve m is closed, the air no longer being supplied to the cylinder k', the weight h² forces the piston back with a cushioned movement, the air escaping around the piston.

The circuit of the generator g consists of wires 2 3 from either terminal thereof, having branches 4 connecting them, and including the lamps n, of any suitable or usual construction, placed in the different apartments, as may be desired. The branches 4 also include switches o, by which they may be opened or closed to put the lights in operation or to extinguish them.

In order to keep the resistance uniform in the lights that are in operation when one or more of the lights n are extinguished, branches 5 are employed, containing resistances equal 5 to that of the lamps n , the resistance preferably being that of similar lamps, n' , which may be placed in any apartment where it is desired to always have more or less light, so that as the lights n are extinguished the substitute lamps n' will be set in operation, the switches o being arranged to close the branch 10 5 in the movement by which they open the branches 4.

In order that the generator may be set in 15 operation whenever one or more of the lights n are to be used, the circuit 6 of the battery B and magnet m' , controlling the valve m , and through it the valve h , is provided with closing branches 7, including switches o' , mechanically connected with the switches o , so that when the latter are moved to open or close the branches 4, containing the lights n , the branches 7 will also be opened and closed; and it is only when all the said branches are 20 25 opened, or all the lights n thrown out of operation, that the said circuit 6 will be opened, causing the valves m and h to close; and thus stopping the motor.

If desired, the switches o o' may be operated automatically, as by an electro-magnet, p , included in that portion of the branch 4 which is left open when the branch 5, containing the substitute lamp n' , is closed.

The switch will be provided with an armature for the said magnet p , which, so long as the branch 4 remains closed, will retain the switch o p' in position to close the branches 4 and 7; but in case of the breaking of the branch 4, as by the destruction of the lamp n 35 40 therein, the switch, being no longer held by its magnet, will be moved by its retracting-spring p' to close the branch 5.

The reservoirs b are provided with pressure-gages r , the pointer of which forms a portion 45 50 of a local circuit, 8, containing a signal, t , the said pointer of the gage being arranged to close the said circuit when the pressure in the reservoirs rises above or is reduced below a certain amount, it thus indicating in the latter case that the supply of power is becoming exhausted.

In other applications, No. 121,710, filed February 23, 1884, and No. 133,547, filed June 2, 1884, I have shown similar apparatus for generating and distributing power and converting the same into electricity, and the claim 55 in the present application is solely for combinations of appliances not claimed in the said applications.

I claim—

1. In an apparatus for electric lighting, a sub-station containing a mechanical motor and electric generator actuated thereby, combined with an electro-magnet controlling the application of power to the motor, and circuit therefor having closing branches, a circuit for the generator having branches containing lamps, and switches controlling the lamp-circuit and circuit of the controlling-magnet, substantially as described. 60 65 70

2. In a system of electric lighting, the following elements in combination, namely: a main station containing a fluid compressor and reservoir, sub-stations, each containing a reservoir connected by pipes with the main reservoir, a motor and electric generator actuated thereby, an electric circuit from the said generator, having branches containing the lamps to be used, and independent branches containing substitute lamps, and switches 75 80 whereby one of the said branches is closed when the other is opened, substantially as described.

3. In an electric-lighting apparatus, a motor and electric generator actuated thereby 85 and connected in circuit with the lamps, combined with a valve controlling the application of power to the motor, and an actuating cylinder and piston for the said valve, and a valve and actuating electro-magnet controlling 90 the admission of fluid to the said cylinder, and a circuit for the said magnet, having controlling-switches, substantially as described.

4. An electric circuit having branches containing electric lamps and other corresponding branches containing substitute lamps, combined with a switch or circuit-changing device controlling both branches, as set forth, whereby the branch containing the substitute 95 100 lamp is closed when the corresponding branch is opened, and the reverse, substantially as described.

5. An electric circuit having a branch containing a lamp, and a switch-controlling magnet in the said branch, combined with a corresponding branch containing a substitute lamp, and a switch controlled by the said magnet, and itself governing the condition of both branches, whereby the second branch is 105 110 automatically closed when the first-mentioned branch is broken, substantially as described.

In testimony whereof I have signed my name to this specification in the presence of two subscribing witnesses.

Witnesses: OSCAR GASSETT.
